UNITED STATES PATENT OFFICE.

CHRISTIANA EAGLE, OF WESTON, CANADA.

DESIGN FOR A FRYING-PAN COVER.

SPECIFICATION forming part of Design No. 26,706, dated March 2, 1897.

Application filed January 19, 1897. Serial No. 619,814. Term of patent 7 years.

To all whom it may concern:

Be it known that I, CHRISTIANA EAGLE, a subject of the Queen of Great Britain, and a resident of the village of Weston, in the county of York, in the Province of Ontario, Canada, have invented and produced a new and original Design for a Frying-Pan Cover, of which the following is a specification, reference being had to the accompanying drawings, forming part thereof.

Figure 1 is a plan view of the frying-pan cover. Fig. 2 is a cross-section of the cover, showing its relative position to a frying-pan.

The leading feature of my design consists in concentric perforations, as illustrated in the plan view, Fig. 1.

A is the cover, which is circular in its general contour.

B are the concentric perforations, and C a central perforation. 20

D is a handle of any size or form.

The cover A is crown-shaped with concentric depressions A' and projecting lip A².

What I claim is—

The design for a frying-pan cover or lid 25 herein shown and described.

CHRISTIANA EAGLE.
